ABSTRACT OF THE DISCLOSURE

An attachment to a standard roller chain having the capability of being rapidly converted from an operative position to an inoperative position without being removed from the chain, removing the chain from its installation or affecting the operation of the chain, or without the need for special brackets. The width of the attachment is no wider than the standard width of chain pintles, nor does the attachment prevent the chains from being bent in the opposite direction.

This invention relates generally to the field of roller chain attachments of a type adapted to be secured to individual links of a roller chain for the purpose of transmitting motion to a surface which is free of interconnection with the chain, as the chain moves between two or more sprockets upon which it is entrained. Devices of this type are known in the art, and the invention lies in specific constructional details which permit improved operation.

Attachments of the above-described type normally consist of replacement links having mounting means thereon upon which projections, cams or other structures which extend laterally from the principal axis of the chain to engage articles to be moved parallel to the axis of the chain or to operate by a camming action fixed structures, such as switches, levers and the like.

In some applications, depending upon the nature of the operation being performed, it is desirable to render inactive some of the attachments on a given chain, while allowing others to remain in active position. In prior art constructions, such adjustment normally requires the use of tools to either remove the attachments from the chain, or at least the structures supported by the mounting means, and in other situations, where this is not practical, it is usual to partially disassemble the device with which the chain is used, to permit removal of the chain and the substitution of another chain having the attachments in desired locations. Where such adjustments are frequent, the down time of the machine with which the chain is used is considerable, with a consequent loss in productive capacity and attendant waste of corresponding labor time.

It is therefore among the principal objects of the present invention to provide an improved attachment for use in conjunction with conventional roller chains in which the above-mentioned disadvantages have been substantially eliminated.

Another object of the invention lies in the provision of an improved convertible attachment chain having a pivotally mounted elongated finger which may be selectively positioned in either an inactive location, in which the principal axis of the finger lies parallel to the axis of the chain, or in an active position, in which the principal axis is disposed substantially at a right angle with respect to said axis.

Another object of the invention lies in the provision of structure of the above-mentioned type, in which adjustment may be performed manually, without the use of any tools, and by those possessed of only ordinary skills.

2

Yet another object of the invention lies in the provision of an improved convertible chain attachment in which the cost of fabrication may be of a reasonably low order, with consequent wide sale, distribution and use.

The objects, as well as other incidental ends and advantages, will more fully appear in the progress of the following disclosure, and be pointed out in the appended claims.

Briefly stated, the disclosed embodiment comprises an outer flat member extending between two adjacent ends of a pair of juxtaposed rollers, the member replacing one of the conventional link plates. An elongated flat finger member is pivotally secured for rotation about the axis of a special pivot pin which extends through the coaxially disposed roller. Detent means is provided for selectively maintaining the finger in an inactive position in which the axis of the finger lies parallel to the axis of the chain, or in an active position, in which the axis of the finger is substantially at right angles to that of the chain. The finger is maintained within the detent means by resilient means associated with the pivot pin, movement of the pin along its own axis serving to overcome the resilient means, and permit manual rotation of the finger to the desired position. Thus, when a quantity of attachments are installed upon a standard chain at predetermined intervals, they may be rapidly adjusted to operative or inoperative position by such action.

BRIEF DESCRIPTION OF DRAWINGS

30 In the drawings:

FIG. 1 is a side view of my convertible attachment shown installed in a standard roller chain.

FIG. 2 is an opposite view thereof;

FIG. 3 is a top view thereof showing the elongated finger locked in the first position;

FIG. 4 is a view similar to FIG. 3 but showing the elongated finger in position for rotation.

DESCRIPTION OF PREFERRED EMBODIMENT

40 Referring now to FIGS. 1 through 4, there are shown, for purposes of illustration, standard link plates 10, 12, 22 and 24, rollers 14, pin 18, and retaining clip 38, as found in any commercial roller chain.

Also shown as the parts of my convertible attachment as they would be installed:

An outer flat member 16, having a flat recess section 26 providing a register shoulder 8 and an elongated recessed section 28. This flat outer member replaces plate 24 at a selected location in the chain and overlies two adjacent ends of two different corresponding plates 12.

50 An elongated flat finger 30, having a flat portion 30A and an elongated portion 30B which rest flat in the recesses 26 and 28 respectively of the outer flat member 16 as a first position. A second position at which portion 30B extends outward as shown in phantom in FIG. 2 and 30A locates against register shoulder 8.

A leaf spring 34 which keeps the elongated flat finger 30 either in the first position or the second position.

60 A special pivot pin 18A with a large diameter head 36 at one end, a body diameter compatible with the bore in roller 14 and the bore in one end of outer flat member 16, a third diameter at the other end compatible with the bore in the elongated flat finger 30 and a final diameter at this end compatible with the required dimensions 65 of a standard commercial retaining ring.

A second special pivot pin 18B with a flat head at one end compatible with the counterbore in the other end of outer flat member 16, a body diameter compatible with the bore in roller 14 and the bore in the same end as above in outer flat member 16 and a final diameter compatible with the required dimensions of a standard retaining clip.

Having thus described my invention, I claim as new and desire to secure by Letters Patent:

1. In an attachment for use with a conventional roller chain having a principal axis, and including a plurality of rollers, linking plates, and pins interconnecting said plates and said rollers, said attachment serving as one of said linking plates, and including structure for transmitting motion from said chain in a direction having a component parallel to the axis of said chain upon movement of said chain along said axis, the improvement comprising: said attachment having an elongated flat finger member having a principal axis and first and second ends, and interconnected for rotation to one end of one of said pins for rotation therewith between a first position in which the principal axis of said finger member lies parallel to the principal axis of said chain, and a second position in which said principal axis of said finger member is at a substantial angle with respect to the principal axis of said chain.

2. Structure in accordance with claim 1, including detent means for maintaining said finger member selectively in said first and second positions.

3. Structure in accordance with claim 2, said one of said pins being laterally shiftable with respect to the axis of said chain whereby said finger member may clear said detent means.

4. Structure in accordance with claim 3, including resilient means urging said last-mentioned pin in a direction moving said finger member into contact with said detent means.
